UNITED STATES PATENT OFFICE.

HORACE MELLOR, OF SANFORD, MAINE, ASSIGNOR TO SANFORD MILLS, OF SANFORD, MAINE, A CORPORATION OF MAINE.

PILE FABRIC.

Application filed January 25, 1928. Serial No. 249,330.

This invention relates to the construction of a pile fabric and the main object of the invention is to provide a novel construction in which areas of pile weave alternate with areas of plain weave.

The object of the invention is further to provide such a type of fabric in which the portions of the ground exposed at the face of the fabric display the warps which form the pile and in which the wefts are not displayed.

The object of the invention is further to provide such a type of fabric in which those portions of the ground formed of plain weave are substantially concealed by the pile.

The object of the invention is further to provide such a type of fabric in which the areas preferably consist of blocks of pile weave alternating with the blocks of plain weave ground, the appearance of the face of the fabric is that of substantially rectangular blocks of pile alternating with substantially rectangular blocks of ground composed of pile warps and ground warps with the weft concealed.

A fabric constructed in accordance with this invention produces a very pleasing effect. By varying the dimensions of the alternating areas a wide variety of patterns may be produced. Since only the warps appear or show to any extent at the face of the fabric, when lying flat, various effects may be produced by varying the colors of the ground and pile warps which, for example, may be of mohair or wool, while the weft, which is concealed, may be of cotton.

The invention is herein disclosed in a specific form as a mohair plush or velvet in which the warps composing the pile are of mohair, while the ground warps and wefts are of other suitable fibre, such, for example, as cotton.

Such a fabric, or a fabric embodying the principles of this invention, may be woven by any suitable form of loom, but it is particularly adapted for weaving on a double or two-ply loom wherein two layers of fabric are woven face to face and then separated by severing the pile warps which extend between the two plies of fabric.

In the drawings:

Fig. 1 is a perspective view illustrating a preferred form of weave embodying the invention, the fabric being shown woven double

and before the two plies are separated and the various warps and wefts being shown much exaggerated as to spacing and proportion.

Fig. 2 is a view in perspective of a more or less diagrammatic or conventionalized nature to illustrate the principle of the appearance of the fabric when viewed from the pile face.

In the construction illustrated, the repeat of the fabric takes place longitudinally thereof by groups of eight wefts and the wefts are numbered in Fig. 1 1 to 8, inclusive. The ground warps repeat transversely of the fabric in pairs passing alternately over and under the wefts to form therewith a regular weave and these ground warps in Fig. 1 are indicated as 1^a and 2^a.

The pile warps in the construction illustrated are also arranged in pairs, these pairs alternating transversely of the fabric with the pairs of ground warps, and these pile warps are indicated as 1^b and 2^b.

The pile warps present W-sections, that is, each section of pile warp as it appears in the ground of the fabric is shaped like a W. For example, viewing the pile warp 1^b in the upper left-hand corner of Fig. 1, it will be seen that, viewing the fabric from the face, it passes under the weft 2, over the weft 3, under the weft 4 and that its two arms which form the pile diverge, thus giving it the shape of a W. With the double-ply fabric illustrated, the pile warp 1^b, after passing under the weft 4 in the upper ply, passes into the lower ply under the weft 6, over the weft 7, under the weft 8, thus forming a similar W-section in the lower ply fabric.

The W-sections which, as noted, are arranged in pairs between adjacent ground warps, are staggered on a group of four wefts, that is to say, two adjacent W-sections are concatenated with four successive wefts, as, for example, the wefts 1, 2, 3 and 4, the W-section of the pile warp 1^b being concatenated with the wefts 2, 3 and 4, as already described, and the other W-section 2^b of the pair being similarly concatenated with the wefts 1, 2 and 3.

In the lower ply the same pile warps are similarly staggered and concatenated with the four wefts 5, 6, 7 and 8, the pile warp 1^b

being concatenated with the wefts 6, 7 and 8, as already explained, and the other pile warp of the pair being concatenated with the wefts 5, 6 and 7.

5 Thus it will be seen that longitudinally of the fabric there are four wefts such as 1, 2, 3 and 4 concatenated with the W-sections of the pile warp, then four wefts, such as 5, 6, 7 and 8 unconcatenated with the pile warp.

10 This weave is repeated transversely of the fabric with the W-sections of the pile warp in alternation with the ground warps being concatenated with the same group of four wefts and this repeat may extend to as great a number of pairs of pile warp sections as may be desired. There are thus presented sections of substantially rectangular shape made up of wefts, pile warps and ground warps alternating both longitudinally and transversely of the fabric with sections of plain weave made up of wefts and ground warps. With the double-ply fabric illustrated, the alternation in one ply comes just opposite to that in the other ply.

25 In Fig. 2 the fabric illustrated in Fig. 1 is shown in a somewhat diagrammatic and conventionalized form with the pile cut and looking at the face of the fabric woven as the lower ply in Fig. 1. When such a fabric is beaten up, the ground and pile warps appearing between the diverging arms of the W-sections of the pile warps 1^b and 2^b conceal the weft, so that on the face of the ground in these sections appears only ground warp shown in Fig. 2 in black and pile warp shown hatched. But between the converging arms of adjacent W-sections of pile warps the ground is composed solely of ground warps and wefts, the weft being shown in Fig. 2 in white. But as the pile formed by the arms of the W-sections of the pile warp fluff out, these sections of plain weave made up of weft and ground warps underneath the converging arms of adjacent W-sections of pile warp are concealed. Consequently while the fabric is made up of substantially rectangular sections of pile weave alternating with substantially rectangular sections of plain weave, the sections of ground which actually show at the face of the fabric are those sections of ground between the diverging arms of pile wherein the ground is composed of pile warps, ground warps and wefts with the wefts concealed.

55 It will thus be seen that this type of fabric lends itself to a wide variety of designs based upon the dimensions and arrangements of the alternating blocks of pile weave and ground weave and that a variety of color effects may be produced depending upon the colors of the pile and ground warps. It will also be seen that when the fabric is woven as a double-ply fabric, there is no waste of pile warp because the pile weave sections alternate with the plain weave sections.

Having thus described the invention, what is claimed as new, and desired to be secured by Letters Patent, is:

1. A pile fabric comprising wefts, pile warps and ground warps in which the pile warps and the ground warps alternate in pairs, the ground warps of each pair passing alternately over and under the successive weft, in which the pile warps are of W-form concatenated with groups of four wefts separated by groups of four wefts unconcatenated with the pile warps and in which the concatenation of the pairs of pile warps with the wefts is repeated transversely of the fabric a plurality of times with the same groups of four wefts and then alternately with the intermediate groups of four wefts, whereby a checkered effect is produced with the pile warp in the ground between the diverging arms of the W-sections of the pile warp and with the ground sections unconcatenated with the pile warps substantially concealed by the converging arms of adjacent W-pile warp sections.

2. A pile fabric comprising wefts, ground warps and pile warps consisting of W-sections in which pile areas conceal areas of plain ground and alternate longitudinally of the fabric with areas of plain grounds, the said W-sections being arranged in pairs, one W-section of which passes under, over and under three successive wefts and the other W-section of which passes under the weft the first section passes over, over the next weft and under the fourth successive weft, whereby the pile warps appear on the face of the plain ground areas between the diverging arms of the W-sections, and the pairs of W-sections being spaced no further apart longitudinally of the fabric than will allow the arms of the W-sections of successive pile areas to conceal the intermediate areas of plain ground which contain no pile warp.

3. A pile fabric comprising wefts, ground warps and pile warps consisting of W-sections which are arranged to form substantially rectangular pile blocks, alternating both longitudinally and transversely of the fabric with substantially rectangular blocks of plain ground, the said W-sections being arranged in pairs, one W-section of which passes under, over and under three successive wefts and the other W-section of which passes under the weft the first section passes over, over the next weft and under the fourth successive weft, whereby the pile warps appear on the face of the plain ground in the blocks between the diverging arms of the W-pile sections, and the pile blocks are spaced no further apart longitudinally of the fabric than will allow the arms of the W-sections of successive pile blocks substantially to conceal the blocks containing no pile warp.

4. A pile fabric having the construction defined in claim 2, in which the repeat lon-

5 longitudinally of the fabric is in groups of eight wefts with the areas of plain ground containing no pile warps containing four wefts and with these areas substantially concealed by the arms of the W-pile sections of successive pile areas.

5. A pile fabric comprising the construction defined in claim 3, in which the repeat

longitudinally of the fabric is in groups of eight wefts with the blocks of plain ground containing no pile warps containing four wefts.

In testimony whereof, I have signed my name to this specification.

HORACE MELLOR.
